UNITED STATES PATENT OFFICE

WILLIAM H. WOOD, OF CLEVELAND, OHIO

VEHICLE HEADLIGHT

application filed January 24, 1923. Serial No. 614,694.

This invention relates to vehicle headlights and has for its object the provision of a simple and easily made sheet metal reflector which shall produce a legally acceptable and practically satisfactory distribution of light without the use of lenses, prisms, shades, dimmers or other expensive, fragile, or light killing devices. The present and prospective legislation of the different States and municipalities requires all light rays to be kept below a certain fixed angle while affording a minimum strength of beam in other regions slightly below the horizontal, while the requirements of easy driving necessitate a restriction of the intensity at points near the vehicle in order to increase the visibility of objects at a greater distance ahead of the vehicle. These two considerations practically require a concentration of the reflected rays inside a rectangular or elliptical space whose major dimension is horizontal. In addition it is desirable that the adjustment requirements be not unduly exact or sensitive, both to facilitate its use by unskilled persons and to minimize the difficulty occasioned by accidental change in adjustment.

A plain paraboloid reflector is inadequate to produce these results, both because of the straying of some portions of the light beam and the streaky character of other portions, as well as the impossibility of securing this distribution except by the assistance of expensive and fragile lenses. It is possible to secure a measurably satisfactory character of light distribution by the use of a combination of paraboloid segments, although the focussing requirements are sometimes unduly exact and it is difficult to join the different segments in a smooth manner so as to enable easy polishing. Combinations of flat surfaces and of corrugated surfaces have also been attempted, but these are difficult to make and are even more difficult to re-polish in case of need.

I have now discovered a new, mathematically-definite surface so located relatively to the light source as effectually to control all parts of the light beam with a high degree of exactness, and likewise devoid of all sharp angles, edges, or corrugations, thus enabling

ready manufacture and easy renovation. Another feature of my improved surface is that the character of the light beam thrown thereby is almost entirely independent of the shape or size (within comparatively broad limits) of the light source or its longitudinal position inside the reflector.

In the drawings accompanying and forming a part of this application I have illustrated the mode of generating my improved reflector surface together with a finished reflector embodying the same. In these drawings Fig. 1 is a diagram showing the mode of generating a true parabola; Fig. 2 is a similar view showing the mode of generating my improved curve as employed for the top of my reflector; Fig. 3 shows the mode of generating the curve employed for the bottom of the reflector; Fig. 4 is a vertical sectional view of the reflector showing the relative position of the two segments; Fig. 5 is a face view of the reflector showing the mode of connecting the segments together; Fig. 6 is a view of the light pattern as thrown on a vertical screen; Figs. 7, 8, 9, and 10 are diagrammatic views showing the reflector segments assembled together with different relative positions of the points S and S' together with the position of the light source relative thereto.

In Fig. 1, A—A is the geometrical axis, D—D the directrix, V the vertex, and f the focal point of the parabola A¹, the nature of the parabolic curve being such that every point of the same is equally distant from the focal point and from the directrix which is a straight line. Therefore $fv=va^1$; $fb=bb^1$; $fc=cc^1$; $fd=dd^1$.

Inasmuch as no known practical source even approximates the size of a geometrical point a true paraboloid produces reflected rays of all kinds even where the source is focussed as accurately as possible; indeed a single point source if displaced from the axis will itself produce all kinds of rays since the direct rays which fall behind the parameter are converged as seeming to originate from forward of the focal point and those which impinge forward of the param-

eter are diverged as seeming to originate behind the focal point.

The essence of my invention resides in displacing the focal point vertically from the 5 axis and then correcting every point of the curve to compensate for this displacement. To do this I draw a line 1—1 to represent the horizontal geometrical or x -axis and above it I located the point s , say $\frac{1}{4}$ inch 10 therefrom. Through this point I draw a vertical line two inches long touching the axis at 2. This line corresponds to the parameter of a parabola and the upper end 3 of this line is a point of the curve at which 15 its inclination to the axis 1—1 is exactly 45° . Also at a point in the rear of the line 2—3 I draw a parallel line D—D, at the same distance from the point 3 as 3 is distant from 2. Thus far the procedure conforms exactly 20 to that followed in drawing a true parabola, symmetrical about the horizontal or x -axis with its vertex tangent to the y -axis.

I now draw an inclined line through the point S so as to intersect both the axis 1—1 25 and the probable curve, say the line e intersecting the axis at 4. I then draw a perpendicular E E the same distance behind the line D D that 4 lies in front of 2, and on the line e locate the point 5 which is equidistant from the line E E and the intersection 30 4.

I then draw another inclined line g through the point S intersecting the axis at 6, and also draw a corresponding directrix 35 G G as far behind D D as the point 6 lies in front of the point 2. On this line g I then find the point 7 which is equidistant from the point 6 and from the line G G. I repeat the same performance for a sufficient 40 number of other lines, h , i (etc.) to locate other points 8, 9, 10, 11 (etc.) and plat an accurate curve between the parameter and the vertex.

I then draw an inclined line j through the 45 point S intersecting the axis at 12 between the parameter and the vertex and to accompany it I draw a perpendicular J J as far in front of the line D D as 12 is distant from 2, after which I find the point 13 on this 50 line equidistant from the point 12 and the line J J. This is repeated for the lines k and K K giving the points 14, 15 and as many other times as desired, after which a curve Y is drawn connecting the points 3, 5, 55 7, 9, 13, 15. This curve is restricted to the region above the line 1—1.

To plat the line below the axis I draw a second line 20—20 as in Fig. 3 and place at $\frac{1}{4}$ inch above it a point S' from which I 60 drop a perpendicular intersecting the axis at 21; and on this line at about $2\frac{1}{4}$ inches (more or less, but preferably a little more than the distance 2—3 for a reason to be explained hereafter) I locate the point 22 65 which is a point on the curve. Also below

the axis and on the other side of the vertex I draw the perpendicular P P, so that the point 22 shall be equidistant from 21 and from P P.

I then draw an inclined line q through the point S' intersecting the axis at 23 behind the point 21 and I also draw a second perpendicular Q Q the same distance in front of P P as 23 is behind 21. On this line I then locate the point 24 equidistant from the point 23 and from the line Q Q. After repeating this with other lines r , t , etc. to find the points 26, 28, etc., sufficient in number to produce an accurate curve, I draw other lines as u intersecting the axis at 29 in front of the point 21 and for each I draw a corresponding perpendicular as U U an equal distance behind the line P P, thus finding the points 30, 32, etc. in the same fashion. I then connect the points 22, 24, 26, 28, 30, 32 producing the curve Z.

I then rotate each curve perpendicular to its plane, the curve Y about the axis 1—1 and the curve Z about the axis 20—20, to form a partial surface of revolution and I 90 assemble these together as shown in Fig. 4 with their axes coinciding and the points S, S' spaced longitudinally apart, with the point S at the rear. If the distance 21—22 was properly chosen relative to the distance 2—3, the vertices of the two curves will 95 match properly with the desired longitudinal separation of these points—say $\frac{1}{4}$ inch. Also the forward end of the lower segment is slightly wider than that of the upper segment enabling the two to be joined at the sides by wing portions X X as described and claimed in my Patent No. 1,235,275, issued July 31, 1917, preventing glare from the lateral portions of the reflector since these wings are leaned toward each other at every point. I preferably make these wings rather wide at the front and tapering rapidly rearwardly as this produces a better placing of the reflected rays and also enables the 100 smooth joining of the different segments. The heel of the reflector is formed with a socket-hole W in line with the points S, S' and the light source, which is generally an electric light filament is located between 105 these two points, the reflector being leaned rearwardly a slight amount so as to elevate the axis 1—1 above the horizontal, but without elevating the reflected rays above the horizontal. This compensates for the separation of the two points S, S' .

The lamp filament is indicated at L. In the case of the usual paraboloid reflector the effect of elevating the light source above the axis would be to cause all rays striking the reflector as if originating ahead of the parameter to be converged and those striking the reflector as if originating behind the parameter to be diverged, thus creating an upwardly converging glare from the lower for 110 115 120 125 130

ward part and an upwardly diverging glare from the upper forward part; but by the peculiar conformation herein provided no upward rays can be produced unless the 5 light source be located either forward of S^1 or rearward of S and by making the distance between these at least as great as the length of the largest commercial filament a lamp is produced which is peculiarly insensitive 10 to focussing. Each ray of light falling on any part of the vertical zone has the same effect as though it came from a point on the axis at some distance beyond the point S , or at some nearer point within the point S' , 15 these points accordingly constituting what might be called virtual foci and these virtual foci are progressively spaced along the axis. The curve can be considered as a compound parabola wherein the foci of successive segments are progressively displaced 20 along the axis. Also this same adjustment of the curve for the vertical displacement removes sensitiveness in all other respects and further produces exactly the pattern of 25 light beam desired, namely an oblong field, since the same correction which serves to compress the rays in a vertical plane serves to spread them horizontally. Likewise every part of the field is illuminated at all 30 times by diverging rays from one part of the reflector and by converging rays from another part thereof, thus producing a uniform, diffused illumination; and if by minor variations in the position of the lamp 35 filament one set of rays should be weakened, the effect of another set of rays will be strengthened, thereby keeping all parts of the field illuminated to substantially the same degree unless the focussing limits be 40 exceeded. Owing to the occurrence of this action in three dimensions it is possible to illustrate the path of these rays only in the vertical plane since all other regions of the reflector are subjected to a cross fire of rays 45 and the path of the reflected ray is seldom or never in the same plane with that of the incident ray.

It will be obvious that any light source of infinitely small size located exactly on 50 either point S or S^1 will have its reflected rays sent forward parallel to the axis 1—1 and that if it be moved to the rear of the point S^1 all rays reflected by the segment Z will be deflected below the axis 1—1. Likewise if it be moved forwardly of the point 55 S all rays reflected by the segment Y will be deflected below the axis 1—1 and the rate of such deflection will remain sensibly equal over a considerable range of adjustment.

60 This same result is achieved simultaneously by the separation of the two points S and S^1 , the light source remaining between them, and the superposed beams are deflected downwardly past the axis so that it is desirable to incline this axis upwardly to pre-

vent the light striking the ground too near the vehicle. See Fig. 7.

It may be noted, however, that it is perfectly feasible to locate the point S ahead of the point S^1 and compensate for the resulting upward deflection of the compound beam by a downward inclination of the reflector axis as shown in Fig. 8.

Furthermore it is possible by inclining the axes of the respective portions Y and Z to obtain the same optical results as by an axial shifting of the points S , S^1 . Thus if the lower segment be tipped downwardly as shown in Fig. 9 the same optical result is obtained as by the arrangement shown in Fig. 4, the light source being located ahead of these points. Likewise if the upper segment be tipped downwardly as shown in Fig. 10 the same optical result is obtained as by the arrangement shown in Fig. 8 if the light source be kept behind the points S , S^1 .

I believe that this is a new mathematical curve. It will be understood that the sizes and dimensions I have given are merely specimens of what may be done and not limitations as to what must be done, also that in my drawings I have greatly exaggerated the elevation and separation of the points S , S^1 , as compared to the parametral radius of the curve. This particular curve is mathematically known as a "cubic" and when accurately made is defined by the equation

$$y - cy^2 - 4pxy + 4cx^2 = 0$$

wherein p represents the abscissa and c the ordinate of the point S or S' . The heel portion of this curve is practically indistinguishable from the heel portion of a parabola whose focal point coincides with S or S' and whose vertex falls on the cubic and whose axis is inclined to the x -axis at an oblique angle whose abruptness increases with increase of c relative to p , being zero when c equals zero. The points S , S' exhibit many of the characteristics of a focal point.

According to another point of view the portions of the curve above the center of the reflector may be referred to the reflector axis as a modified semi-parabola in which the focal length increases from the limb toward the vertex in such a manner that all focal lines pass substantially through a selected point located above such axis, which point thus becomes the virtual focus of such curve; while the portion thereof below the center of the reflector may be considered as a modified semi-parabola in which the focal length decreases from the limb toward the vertex in such a manner that all focal lines pass substantially through a selected point also located above the reflector axis. These curves, in whichever way they be defined,

are employed as generators for defining the reflector surface, or at least that part of the same lying at and near the central longitudinal vertical plane; and conversely the reflector surface whose intersection with a vertical axial plane exhibits the curves herein defined contains the invention which it is my purpose to claim and secure.

I have illustrated in detail only the type in which the source is elevated above the geometrical axis, but it will be apparent that the same adjustment can readily be made for a source located beneath the axis and the resulting curve built into a reflector. Such a device exhibits no advantages over the one herein illustrated and contains the defect that the two halves do not match each other so well and are more difficult to join.

While I have described my invention as though the different reflector sections were in fact made of sheet metal segments joined together, it will be understood that what is in fact done is to form these surfaces upon a rigid massive punch and by the use of a suitable die stamp or draw the reflectors out of sheet metal with the various portions integrally connected together. Such a reflector exhibits a slightly oval front but contains no corrugations, sharp angles, or reentrant surfaces and can be plated and polished by machine methods as easily as a plain paraboloid.

The essence of this invention resides in my new curve and the mode of compensating by the one act for all variations encountered in headlight practice, but I do not limit myself to the particular method of laying out the curve hereinbefore described since the same substantial generator by whatever mathematical or drafting process it be identified falls within the purview of my invention, and I do not limit myself as regards the angular extent of the generator employed or the angular extent of the rotation of such generator about any axis of revolution except as specifically recited in my several claims.

Having thus described my invention what I claim is:

1. In a headlight, a reflector having its upper portion conforming to a surface of revolution about a substantially horizontal axis of a generator which has for a focus a point which is displaced above the axis of revolution, and having its lower portion also conforming to a surface of revolution about a substantially horizontal axis of a second generator which has for a focus a point which is displaced from the geometrical axis of said second generator, said two axes of revolution being located in the same vertical plane.

2. In a headlight, a reflector having above its central horizontal plane a surface de-

fined substantially by the transverse movement of a generator which consists of a modified semi-parabola whose focal length constantly increases from its forward limb to its vertex in such a manner that all focal lines pass substantially through a selected point above the parabolic axis which point thus becomes the virtual focus of such generator.

3. In a headlight, a reflector having below its central horizontal plane a surface defined substantially by the transverse movement of a generator which consists in effect of a modified semi-parabola whose focal length constantly decreases from its forward edge to its vertex in such a manner that all focal lines pass through a selected point above the parabolic axis, which point thus becomes the virtual focus of the generating curve in said vertical plane.

4. In a headlight, a reflector whose uppermost segment consists of a surface substantially defined by the transverse movement of a generator which consists essentially of a modified semi-parabola whose focal length increases from its forward limb toward its vertex, and whose lowermost segment consists of a surface substantially defined by the transverse movement of a different generator which consists essentially of a modified semi-parabola whose focal length decreases from its forward limb toward its vertex, the focal lines of each generator passing substantially through a selected point above the corresponding parabolic axis which point thus becomes a virtual focus for its respective generator.

5. A headlight having the portion of its reflector directly above its axis substantially defined by a curve which is essentially a modified semi-parabola whose focal length constantly increases from its forward edge toward its vertex in such a manner that all focal lines pass through a selected point above the parabolic axis, which point thus becomes the virtual focus of the curve; and having the portion of its reflector directly below its axis defined by a curve which is essentially another modified semi-parabola whose focal length decreases constantly from its forward edge to its vertex in such a manner that all focal lines pass through a selected point above such second parabolic axis which point thus becomes the virtual focus of such lower curve, both of said points and both of said virtual foci being located in the same vertical plane, a light source located above both parabolic axes and the two sides of said reflector being closed by portions whose normals all pass below said light source.

In testimony whereof, I hereunto affix my signature.
